Inventor,
Adelard J. Gauthier,

By Milton Tibbets, Atty.

UNITED STATES PATENT OFFICE.

ADELARD J. GAUTHIER, OF DETROIT, MICHIGAN, ASSIGNEE TO PACKARD MOTOR CAR COMPANY, OF DETROIT, MICHIGAN, A CORPORATION OF MICHIGAN.

ROD AND METHOD OF MAKING SAME.

1,415,091.

Specification of Letters Patent.

Patented May 9, 1922.

Application filed March 20, 1920. Serial No. 367,480.

To all whom it may concern:

Be it known that I, ADELARD J. GAUTHIER, a citizen of the United States, and resident of Detroit, Wayne County, State of Michigan, have invented certain new and useful Improvements in Rods and Methods of Making Same, of which the following is a specification.

This invention relates to rods and more particularly to yoke ended rods and to methods of making such rods.

In many machines, such for instance, as motor vehicles, it is necessary or desirable to provide for lost motion in the connections between two operative elements of the machine. For this purpose it is common to use connecting links or rods having slotted or bifurcated end portions or yokes.

This invention has for one of its salient objects, to provide a rod of this character that will be rigid and strong in construction and that may be inexpensively manufactured.

Another object is to provide a method of making rods of this character by means of which they may be manufactured cheaply and efficiently.

Other objects will appear from the following description taken in connection with the drawings which form a part of this specification and in which:

Fig. 1 is a view in elevation showing the body portion of the rod, this showing being broken away;

Fig. 2 is a view similar to Fig. 1, but showing the body portion after one end has been swaged;

Fig. 3 is an edge view of the flat bar stock from which the yoke or slot portion of the rod is made;

Fig. 3^a is a transverse sectional view of the bar shown in Fig. 3;

Fig. 4 is a view similar to Fig. 3 but showing the slot portion or yoke of the rod after the flat bar has been bent upon itself and the free ends have been swaged;

Fig. 5 is an end view of the construction shown in Fig. 4;

Fig. 6 illustrates another form of end portion open at one end and which is formed from a pair of flat bars instead of from a single bar, this view corresponding to Fig. 4;

Fig. 7 shows the yoke illustrated in Fig. 4 butt welded to the body portion shown in Fig. 2; and

Fig. 8 is an edge view taken at right angles to Fig. 7 showing the yoke ended rod after the joint has been machined to remove the excess metal.

Referring to the drawings, the body portion 20 of the yoke ended rod is preferably formed of tubular material for strength, and in this case the first step in the method of making the rod consists of swaging one end of the tubular rod as shown at 21, the tubular rod being closed at this swaged end to form a solid rod.

The yoke or slot portion illustrated in Figs. 3 to 5 inclusive is shown as formed from flat bar stock shown at 22, this bar 70 being bent upon itself as shown in Fig. 4, the side portions 23 of the slot being spaced apart. The free ends of the bar are then swaged as shown at 24 to a position in which they are juxtaposed with respect to each 75 other, thereby closing the slot. The two juxtaposed ends 24 of the yoke are then simultaneously butt welded as shown at 25 to the end 21 of the body portion 20 of the rod and this joint is then finished by machining or in any other suitable manner to remove the excess metal.

In the form of the invention illustrated in Fig. 6, the slot portion of the rod is formed of two separate pieces of material or bars, 85 26, each of these pieces having one end offset and swaged as shown at 27, the ends 27 being positioned in a manner similar to the ends 24 of the bar 22. The ends 27 of the bars 26 are then butt welded to the end of 90 the body portion in the same manner as the ends 24.

From the above description it will be seen that I have provided a simple and inexpensive method of manufacturing yoke ended 95 rods and that the rods so manufactured will be rigid and strong in construction.

While I have, in the above specification, described certain specific embodiments of my invention, it will be understood that the invention is not limited to the exact method or details of construction specifically illustrated and described, but that changes may be made without departing from the spirit or scope 100 of the invention as expressed in the following claims.

Having thus described my invention, what I claim and desire to secure by Letters Patent is:

1. A rod formed of tubular material hav-

- ing a slot portion at one end thereof, the portion of the rod adjacent to the slot portion being solid.
2. A rod formed of tubular material having integrally united therewith, at one end, a slot portion, the portion of the rod adjacent to the slot portion being solid.
3. A rod having a body portion formed of tubular material and having a slot portion at one end formed of flat bar material, said body portion and said end portion being integrally joined.
4. A method of forming a rod which consists of swaging one end of a tubular body portion, forming a slot member having free ends swaged into juxtaposition with respect to each other, and welding the juxtaposed ends of the slot member to the swaged end of the tubular member.
5. A method of forming a rod which consists of compressing one end of a tubular body portion in a manner to close said end, bending a bar upon itself to form a slot, positioning the ends of the bar into juxtaposition to close the slot at said end, and welding the closed end portion of the rod to the juxtaposed ends of the bar.
6. A method of forming a rod which consists of swaging one end portion of a tubular rod and butt welding two juxtaposed ends of a slot member to the swaged end portion of said rod.
7. A method of forming a rod having a yoke at one end which consists of butt welding two ends of the yoke portion to one end of the body portion of the rod.
8. A method of forming a rod having a body portion and a slot portion which consists of bending a flat bar upon itself to a form in which the longitudinal portions are spaced apart to form a slot and the free ends are offset to close the slot, and welding the free ends of said slot portion to one end of the body portion.
9. A method of forming a rod having a body portion and a slot portion which consists of swaging one end of the tubular body portion, bending a bar upon itself to a form in which the longitudinal portions of the bar are spaced apart and the free ends are offset to close this slot, and welding the swaged end of the tubular body portion to the free ends of the slot portion.
10. A method of forming a rod having a body portion and a slot portion which consists of swaging one end of a tubular body portion, bending a bar upon itself to a form in which the longitudinal portions of the bar are spaced apart, swaging the free ends of the bar to close the slot, and butt welding the swaged ends of the slot portion to the swaged end of the body portion.

In testimony whereof I affix my signature.

ADELARD J. GAUTHIER.
